UNITED STATES PATENT OFFICE.

LUTHER BRYANT, OF MAPLE GROVE, MAINE.

RATCHET-WRENCH.

SPECIFICATION forming part of Letters Patent No. 372,654, dated November 8, 1887.

Application filed June 3, 1887. Serial No. 240,159. (No model.)

To all whom it may concern:

Be it known that I, LUTHER BRYANT, a citizen of the United States, residing at Maple Grove, in the county of Aroostook and State 5 of Maine, have invented a new and useful Improvement in Ratchet-Wrenches, of which the following is a specification.

My invention relates to improvements in ratchet-wrenches; and it consists in a certain 10 novel construction and arrangement of parts for service, fully set forth hereinafter, and specifically pointed out in the appended claims.

In the drawings hereto annexed, Figure 1 is a side view of the wrench. Fig. 2 is a longitudinal section thereof. Fig. 3 is a transverse section on the line *x x* of Fig. 2. Fig. 4 is a detail view of the collar. Fig. 5 is a detail view of the pivoted pawl attached to the link which operates on the jaws.

Referring to the drawings, in which similar letters denote corresponding parts in all the figures, A designates the shank of the wrench, having the handle B on the lower end, and the upper end is bifurcated to provide the ears A' 20 A', having the slot *a* therebetween, and the said ears are extended to form the collars A² A². Through the aligned openings in the said collars passes the shaft C, having the disk D thereon to operate in the space between the 25 said collars, and having ratchet-teeth on its periphery, for a purpose hereinafter explained. The said shaft is extended on one side of the shank to form the upper or rigid jaw, E, of the wrench, the said jaw having a longitudinal slot, *e*, therein.

F is the movable jaw, having a plate or tongue, *f*, on the upper side pivoted in the slot *e* in the rigid jaw. A leaf-spring, G, is secured 30 on the upper side of the rigid jaw and adapted to operate at the free end in the slot *e* to actuate the movable jaw and normally hold it away from the rigid jaw.

H designates a swinging link, the lateral arms *h* of which are pivoted on opposite sides 45 of the rigid jaw, and between the lower or free ends of the said arms is pivoted the pawl I, which is provided on the under side with the teeth *i*, and I' is a thumb-hold or handle formed thereon, to enable the said pawl to be raised 50 to disengage it.

The lower side of the rear portion of the lower jaw is segmental in outline, and is pro-

vided with ratchet-teeth to be engaged by the above-mentioned pawl I. It will be seen that by swinging the lower end of the link H rearwardly the lower jaw is raised, and as the pawl I engages with the ratchet-teeth at any point, any desired adjustment of the lower jaw may be made to have the desired distance between the jaws. To close the jaws it 60 is merely necessary to draw the lower or free end of the link rearwardly, the teeth on the lower side of the pawl sliding over the teeth of the segmental ratchet; and to open the said jaws raise the handle or thumb-hold of the 65 pawl, and the teeth are disengaged and the lower jaw is free to be moved. As the spring G normally presses downwardly on the said lower jaw, it will be seen that when the handle of the pawl I is moved the said jaw will be thrown 70 down. The opposite end of the shaft is hollowed out to form a sleeve, *l*, and in the said sleeve is secured the hand-rest K, to enable the operator to hold the jaws of the wrench in close contact with the nut to which they are 75 applied.

L L designate pivoted spring pawl-levers operating in the slot *a* in the upper end of the shank and adapted to normally engage in the ratchet D. The said pawl-levers are adapted, 80 when the lower ends thereof are pressed upon, to be lifted out of engagement with the said ratchet.

M designates a collar operating on the upper end of the shank below the lower ends of 85 the pawls L, and on the upper edge of the said collar is formed a segmental flange, N, which extends not quite one-half the distance around the collar, and the inner side of the said flange, at the ends thereof, is slightly beveled to enable 90 the flange to slide over and depress the lower ends of the said pawls and lift the same from engagement with the ratchet.

The flange, as before stated, does not extend quite half-way around the collar, and consequently only one of the pawls can be lifted at one time, thus enabling the handle to be turned in one direction. When the other pawl is lifted, the handle may be turned in the opposite direction. Also, the collar may be so disposed as not to lift either pawl, and then the handle will be locked in both directions, as will be readily seen.

I am aware that it is not new to provide a

wrench with a ratchet and handle having a pawl thereon to enable the same to be turned in either direction, and I do not claim this broadly.

5 I am further aware that it is not new to provide a wrench with a hinged or pivoted movable jaw, and I do not claim it. The peculiar arrangement and combination of the parts as herein shown and described are, however, 10 new, and are extremely simple and effective in operation.

The operation of the wrench is well known to those skilled in the art to which it pertains, and a detailed description thereof need not be 15 here given.

Having now described the construction, operation, and advantages of my invention, what I claim, and desire to secure by Letters Patent of the United States, is—

20 1. In a wrench, the combination of the handle A, collars A² A² on the upper end thereof, the shaft C, mounted in the said collars and extended on one side thereof to form the rigid jaw E and on the other side to form the socket 25 or sleeve k, the hand-rest K, secured in the said socket, movable jaw F, pivoted to the rigid jaw, the spring G, to hold the jaws normally open, and means, substantially as described, to close the jaws, substantially as specified.

25 2. The combination of the shank A, parallel collars A² on the upper end thereof, shaft op-

erating in the openings in the said collars, disk D between the collars and having ratchet-teeth thereon, spring-pawls to engage the teeth, sleeve k on one end of the shaft, hand-rest K therein, upper jaw, E, formed on the other end of the shaft, having a slot, e, therein, movable jaw F, having a tongue or plate, f, pivoted within the said slot, toothed segment on the said lower jaw, link H, pivoted to the rigid jaw, and having a pivoted pawl to engage in the ratchet-teeth in the lower jaw, and the spring G, to actuate the movable jaw, all constructed and arranged substantially as and for the purpose set forth. 45

3. A wrench having the rigid jaw E, movable jaw F, pivoted thereto and having a toothed segment thereon, link H, pivoted to the rigid jaw, pivoted pawl I in the free end of the said link, having teeth to engage in the said toothed segment, thumb-hold I' on the said pawl, to enable the same to be raised, and the spring G, to normally hold the jaws separated, all constructed and arranged substantially as and for the purpose set forth. 55

In testimony that I claim the foregoing as my own I have hereunto affixed my signature in presence of two witnesses.

LUTHER BRYANT.
